FUEL GRATE SECTION FOR HEATERS

Napoleon J. La Tulip, Oswego, N. Y.

Application December 15, 1932, Serial No. 647,369

3 Claims. (Cl. 126—163)

This invention relates to a fuel grate section for heaters and is adapted to be used more particularly for burning the finer grades of hard or soft coal under forced draft but may be used for burning wood.

The main object is to obtain an even distribution of air from the underside upwardly through and across the entire area of the grate and the fuel thereon for effecting complete combustion of all of the fuel and at the same time to allow the resultant ash to pass downwardly through the openings in the grate and into the underlying ash pit or box, not shown.

One of the specific objects is to provide the grate with a multiplicity of similar relatively small rectangular or square openings arranged in longitudinal and transverse rows with alternate openings of each row disposed in diagonal relation to the remaining openings for directing the inflowing air over the entire area of the grate and also for permitting free discharge of the ash from the grate without releasing the fuel.

Another specific object is to provide the several openings with separate baffle units removably seated therein and each provided with an enlarged head of greater area than and adapted to overlie its corresponding opening in spaced relation to the upper face of the plate in which the openings are formed for the purpose of deflecting the inflowing air laterally across the top of the grate and at the same time preventing the discharge of the unburned fuel while allowing the discharge of the ash.

Other objects and uses will be brought out in the following description.

In the drawing:

Figure 1 is a top plan of a grate section embodying the various features of my invention in which some of the baffle units are shown in top plan and others in section, the remaining baffle units being omitted.

Figure 2 is a transverse vertical sectional view taken in the plane of line 2—2, Figure 1.

Figure 3 is a perspective of one of the detached baffle units.

Figure 4 is an enlarged sectional view of a fragmentary portion of a modified grate section in which the upper surfaces of the plate around the openings are countersunk.

As illustrated, this grate section comprises a plate 1 of cast metal or other suitable material reinforced by a central lengthwise rib 2 and provided with a multiplicity of similar rectangular, in this instance square, openings 3 and 3' arranged in lengthwise and transverse rows for re-

ceiving the stems of a corresponding number of baffle units 4.

The alternate openings 3 of each row are preferably parallel with each other and with the longitudinal and transverse centers of the plate 60 while the remaining alternate openings 3' are arranged diagonally with reference to said longitudinal and transverse centers and also to the parallel openings, as shown more clearly in Figure 1. 65

These openings are relatively small as compared with the area of the plate but serve as main passages through which the air may pass from the underside upwardly to the fuel for supporting combustion of said fuel and also permitting the precipitation of the ashes therethrough to the underlying ash pit or box. 70

The distance between the openings and also the distance between said openings and side and end walls of the plate is approximately equal (more 75 or less) to the rectilinear distance between opposite walls of any one of said openings so that each plate may contain a maximum number of openings without sacrificing the strength thereof.

The baffle units 4 are preferably made of cast 80 iron or other suitable material and each of said units preferably comprises a circular head 5 and a stem 6, the head 5 being of greater area than the corresponding opening and is adapted to overlie the same in spaced relation to the upper 85 surface of the plate 1, as shown more clearly in Figure 2.

The means for holding the heads 5 in spaced relation to the upper surface of the plate 1 preferably comprises a series of, in this instance four, 90 radially projecting lugs or bosses 7 arranged in uniformly spaced relation circumferentially about the axis of the head and preferably formed integral therewith to extend downwardly therefrom a distance approximately equal to the thickness 95 of the head, as shown more clearly in Figure 2.

These lugs or bosses 7 extend inwardly from the periphery of the head 5 and are adapted to rest upon the upper surface of the plate 1 around the corresponding openings 3 or 3' to hold the 100 major portion of the head in sufficiently spaced relation to the upper surface of the plate to allow the air to pass from the underside upwardly through the openings 3 or 3' and thence through the spaces between the lugs 7 into the 105 fuel for supporting combustion thereof.

The stem 6 is preferably formed integral with the head 5 and is of considerably less cross sectional area than any one of the openings 3 or 3' and is also of sufficient vertical length to extend 110

downwardly from the head through the corresponding opening and some distance below the lower face of the plate 1 for holding the head in more or less coaxial relation to its opening.

5 As illustrated, the stem 6 of each baffle unit comprises a plurality of, in this instance four, radially projecting lengthwise ribs 8 arranged in uniformly spaced relation circumferentially around the axis of the head 5 and preferably 10 integrally united at the center and also to the head, as shown more clearly in Figures 2 and 3.

These lengthwise ribs 8 are preferably arranged in the same planes as the corresponding lugs or 15 bosses 7 so as to form continuations thereof, one of the ribs being provided with a downward extension 9 having a transverse opening 10 for receiving a releasable locking member such as a cotter pin 11 or equivalent locking means, as shown in Figure 2.

20 These pins form individual locking members for the several baffle units but obviously the cotter pins 11 may be substituted by a single wire or equivalent fastening member passing through two or more of the extensions 10, without departing from the spirit of the invention.

The opposite faces of the lugs or bosses 7 are preferably beveled at 12 so as to flare outwardly, the object of which is to direct the inflowing air toward an intermediate radial line between 30 the lugs or rather to distribute the air more evenly around the axis of the head 5 and into the fuel between the heads where it may readily expand through the fuel across the tops of the heads.

35 It will be noted upon reference to Figure 1 that the radial widths of the ribs 8 are equal and that the distance between the outer edges of diametrically opposite ribs is slightly greater than the distance between opposite sides of any one of the 40 openings and it, therefore, follows that in order to insert the stem 6 in its corresponding opening, the diametrically opposite wings must be arranged in alignment with diagonally opposite corners of said opening so that when the stem 45 is inserted in the opening its angular movement is limited by the engagement of the outer edges of the ribs with opposite sides of the opening.

Operation

50 It will be observed that the lugs 7 extend beyond the outer edges of their corresponding ribs 8 so that when the baffle units are inserted in their respective openings, the lower faces of the lugs 7 will rest upon the upper face of the plate, thereby holding the head 5 in spaced relation to the upper surface of said plate, to allow the air 55 to pass from the underside of the plate upwardly through the openings 3 or 3' and through the channels between the ribs 8 and thence outwardly 60 into the combustion chamber through the passages between the head and plate and between the lugs.

The heads 5, therefore, serve the double purpose of preventing direct upward movement of 65 the air from the openings 3 or 3' in the combustion chamber and also prevent the passage of fuel downwardly through said openings while permitting the ash to pass under the marginal edges of the head 5 and thence downwardly through the 70 openings 3 or 3' into the underlying ash pit, not shown.

Under these conditions, hard or soft coal dust 75 may be used as a fuel in which case it may be necessary to use a blower or other forced-draft device for introducing the air into the ash pit

below the plate 1 so that it may pass upwardly through the openings 3 and around the marginal edges of the heads 5 into the combustion chamber for supporting combustion of the fuel.

On the other hand, if wood is to be used as fuel 80 the baffle sections 4 may be removed by upward displacement by simply removing the cotter pins 11, it being understood that when the baffle units are removed they can be laid to one side outside of the heater ready for reuse when it is desired 85 to burn fine coal.

It will also be noted that when the several baffle units are assembled in operative position in their respective openings in the plate 1, the ribs of alternate units will face the spaces between the 90 ribs of adjacent units whereby the inflowing air will be distributed more evenly over the entire surface of the grate and at the same time the ash is free to pass downwardly through the several openings.

95 The construction shown and described is particularly simple, practical and efficient, but obviously various changes may be made in the detail construction without departing from the spirit of the invention.

100 For example, in Figure 4, the upper surface of the grate section as 1' surrounding each opening 3 is depressed or countersunk at 3' to about the same vertical depth as the distances between the lower edges of the lugs 7 and upper face of the head 5 so that when the lugs 7 are seated upon the bottom of the countersunk portion, the upper surface of the head 5 will be on the same level as the upper surface of the remaining portion of the plate 1'. 105

110 The object in bringing the upper surfaces of the baffle members 4 in the same plane as the upper surface of the remaining portion of the plate is to permit the use of a slicing tool or other fuel-loosening member commonly used for breaking up the clinkers to be moved freely across and upon said surfaces without liability of injuring or loosening said baffle members.

115 In view of the countersinking of the upper surfaces of the plate 1' for receiving the heads 5 and the baffle members 4, the adjacent portion of the plate is also depressed for reinforcing purposes to form bosses 3'', the lower faces of which are disposed in approximately the same plane as the lower ends of the stems 6 of the baffle 120 members 4, thus protecting the stems from contact with underlying objects.

125 These bosses are provided with diametrical slots 11' open at the bottom for receiving the cotter pins 11 by which the baffle members 4 are held 130 against accidental displacement.

135 Another purpose of the countersinking of the heads of the baffle members 4 in the upper surface of the plate 1' is to permit the use of a shaking grate resting upon or just above the plate 1' without interference with the baffle members under which conditions it is, of course, understood that the shaking grate will be provided with openings through the ash and air could freely pass.

140 What I claim is:

1. A fuel grate section comprising a plate having a multiplicity of square openings therethrough, and baffle units, one for each opening, having enlarged circular heads of greater 145 area than and overlying their respective openings, each head having spaced lugs on its underside resting upon the upper surface of the plate for holding it in spaced relation thereto and provided with lengthwise ribs projecting into the 150

corners of its opening to hold the baffle plate against turning in said opening.

2. A fuel grate section comprising a plate having a multiplicity of square openings there-
5 through, baffle units, one for each opening, said units having enlarged heads of greater area than and overlying their respective openings, each unit having means for holding it in spaced relation to the upper surface of the plate and also
10 provided with a stem projecting into its opening and provided with lengthwise ribs projecting in-

to the corners of said opening to hold the unit against turning about its axis.

3. In a fuel grate, a plate having a plurality of rows of square openings, alternate openings of each row being turned 45 degrees with reference to the remaining openings of that row, and baffle units inserted in said openings, each unit having diametrically opposite ribs arranged in diagonally opposite corners of its opening to prevent undue angular movement of said unit. 80
